DESIGN FOR A MUSIC BOX

Kenneth C. Shyvers, Seattle, Wash.

Application February 8, 1946, Serial No. 126,380

Term of patent 14 years

(Cl. D56—4)

To all whom it may concern:

Be it known that I, Kenneth C. Shyvers, a citizen of the United States, residing at Seattle, in the county of King and State of Washington, have invented a new, original, and ornamental Design for a Music Box, of which the following is a specification, reference being had to the accompanying drawings, forming part thereof.

In the drawings:

Fig. 2 is a rear elevational view.

Fig. 3 is a side elevational view; and

Fig. 4 is a top plan view thereof.

I claim:

The ornamental design for a music box, as shown.

KENNETH C. SHYVERS.
